ACCUMULATING SYSTEM

Carl Föhl, Berlin, Germany, assignor to Ruths-
accumulator Aktiebolag, Berlin, Germany, a
corporation of Sweden

Application December 17, 1931, Serial No. 581,713
In Germany December 18, 1930

21 Claims. (Cl. 237—56)

My invention relates to an improvement in hot water heating systems and contemplates a hot water accumulator included in such a system with a hot water generator and heat consumers.

5 One of the objects of my invention is to provide a system wherein a constant heat input to the hot water generator may be maintained regardless of variations in demand for hot water.

10 Another object of my invention is to provide a system wherein fluctuations in the heat input may be taken care of, although these fluctuations are not in accordance with the demand of the heat consumers.

15 A still further object of my invention is the provision of such a system which is fully automatic, being controlled by conditions arising in the system due to either or both fluctuations in heat input or in the demand for hot water.

20 Further objects and advantages of my invention will be apparent from the following description considered in connection with the accompanying drawings, which form a part of this specification and on which:

25 Fig. 1 is a more or less diagrammatic view, partially in cross-section, of a preferred embodiment of my invention;

30 Fig. 2 is a more or less diagrammatic view, partially in cross-section, of a modified embodiment of my invention;

35 Fig. 3 is a more or less diagrammatic view, partially in cross-section, of a still further modified embodiment of my invention;

40 Fig. 4 is a more or less diagrammatic view, partially in cross-section, of a portion of the apparatus shown in Fig. 3, but with a fixed orifice substituted in place of a variable valve shown in Fig. 3; and

45 Fig. 5 is a more or less diagrammatic view, partially in cross-section, of a portion of the apparatus shown in Fig. 2, but with the thermostatic element placed directly in the generator.

50 Referring more particularly to Fig. 1, reference character 10 designates a hot water or hot water and steam generator which may be heated by liquid, gaseous or solid fuel or by steam. If steam is employed for heating the contents of the generator, the steam may advantageously be obtained from the discharge of a high pressure steam consumer. Generator 10 is preferably covered with an insulating material 11. A conduit 12 is connected to the upper part of generator 10 and serves as a steam delivery conduit in the event that it is desired to withdraw steam from the generator to be used for any special purpose. However, so far as the present invention is con-

cerned, it is immaterial whether or not any steam is withdrawn. Generator 10 may be supplied with feed water in the usual manner.

5 A conduit 13 is connected to the water space of generator 10 and leads to the intake of a pump 14. A conduit 15 connects the discharge of pump 14 with one or more heat consumers 16. These consumers may be of any nature wherein heat is absorbed from hot water supplied to the consumers, one example being hot water coils in dyeing vats. The inlet of each consumer 16 is provided with a valve 17 which may be manually operable. A conduit 18 connects the discharge of consumers 16 with the bottom of a hot water accumulator 19. Accumulator 19 is preferably arranged in a vertical position and is covered with insulating material 20.

10 A conduit 21 is connected to conduit 18, or might be connected directly to the bottom of accumulator 19, and leads to the water space of 10 generator 10. Within conduit 21 there is disposed a resistance to the flow of fluid there- 15 through. The resistance may be a fixed orifice, a manually operable valve, or an overflow valve. An overflow valve is preferable and is shown on 15 the drawings. Overflow valve 22 is known per se and is arranged to open when the pressure on the supply side of the valve increases to a pre- 20 determined value, and to close when the pressure drops below this value. The valve comprises a 25 valve member 23 mounted on a reciprocable valve stem 24, the other end of which carries a piston 25 slidably mounted within a cylinder 26. The upper end of the cylinder is connected by 30 means of a conduit 27 with conduit 21 on the supply side of the valve. A spring 28 is located 35 in cylinder 26 beneath piston 25 and tends to force the piston upwardly in the cylinder, while the fluid pressure conveyed through conduit 27 to the upper part of the cylinder tends to force 40 the piston downwardly and to thus open the valve.

45 A conduit 29 is connected to conduit 15 and leads to the upper part of accumulator 19. A suitable resistance, such as overflow valve 30, 45 which may be similar in all respects to overflow valve 22, is introduced in conduit 29. A conduit 31 is connected to conduit 29 at a point between overflow valve 30 and accumulator 19, or it might be connected directly to the upper 50 part of the accumulator. The other end of conduit 31 is connected to conduit 21 at a point between overflow valve 22 and generator 10. Conduit 31 might be connected directly to the water space in generator 10. A pressure re- 55

sponsive valve 32 is disposed in conduit 31. Valve 32 is similar to overflow valve 22 except that the valve member is so arranged that an increase in fluid pressure exerted on the piston tends to close the valve against the force of the spring. A conduit 33 connects the upper part of the cylinder of valve 32 with the steam space of generator 10, so that an increase in pressure in the generator tends to close valve 32.

10 The operation of the above described device is as follows:

Assume that generator 10 is being heated at a constant rate, which is sufficient to provide enough hot water for the average requirements 15 of the heat consumers 16. Assume further that at this particular instant one or more of the valves 17 are closed due to the fact that one or more of the consumers are out of use. Pump 14 operates at a constant speed and, due to the 20 fact that one or more of valves 17 are closed, the pressure in conduit 15 will increase. This increase in pressure will be exerted in conduit 29 and will cause valve 30 to open. Due to prior 25 conditions existing in the system the pressure in generator 10 may be such that valve 32 is either shut or open, or partially open. Assume that valve 32 is closed due to a high pressure 30 in generator 10. A portion of the hot water pumped by pump 14 will flow through conduits 15 and 29, due to the fact that one or more of valves 17 are closed, and through valve 30 and into the top of accumulator 19. This hot water will displace cold water from the lower part of 35 the accumulator and this cold water will flow, along with the discharge, if any, from consumer 16, through conduits 18 and 21, the pressure created by pump 14 causing overflow valve 22 to open and thus permitting flow through conduit 21 to generator 10. It will thus be seen that 40 during this period of low heat consumption, cold water will be forced from the accumulator into the generator. Under conditions of low heat consumption the generator is able to take care of this supply of cold water. If, on the other 45 hand, a comparatively low pressure exists in generator 10, due to the fact that a comparatively large amount of steam is being withdrawn through conduit 12, then valve 32 will be open and the hot water flowing through conduit 29 50 may pass through conduits 31 and 21 into generator 10. Thus, under such conditions cold water from the accumulator will not be introduced into the generator.

Assume now that all of valves 17 are open and 55 a peak load condition exists. The pressure in conduit 15 will drop and overflow valve 30 will close. All of the hot water will be supplied to the heat consumers and discharge therefrom in a cooled state through conduit 18. If the pressure in generator 10 is sufficiently high to maintain 60 valve 32 closed, this cold water will pass through conduit 21 to the generator. However, the introduction of this large amount of cold water into the generator will cause the pressure there- 65 in to drop to such a point that valve 32 is opened. The cold water discharged through conduit 18 will now pass into the lower part of accumulator 19 due to the fact that the opening of valve 32 has so reduced the pressure in the system 70 that the overflow valve 22 will close. Introduction of the cold water into the lower part of accumulator 19 will displace hot water from the upper part of the accumulator and this hot water will flow through conduits 29, 31 and 21 into generator 10. Thus, during periods of peak load 75

the generator will be supplied with hot water from the accumulator which has been stored during periods of low load.

If the heat input to generator 10 fluctuates due to any cause, such as uneven firing or variations in steam supply in the event that the generator is heated by exhaust steam from a steam consumer or by excess steam from a steam generator, the system automatically accommodates itself to such changes. In the event that the rate of heating of the generator is low, the pressure in the generator may drop sufficiently so that valve 32 will open. If this happens at a time when one or more of valves 17 are closed, the hot water circulated by pump 14 will pass through conduits 15 and 29, valve 30 being open due to the fact that one or more of valves 17 are closed. This hot water will pass from conduit 29 into conduits 31 and 21 and back to the generator. Overflow valve 22 will be closed under these conditions due 20 to the fact that valve 32 is open and hence prevents a sufficient pressure being built up in the system by the pump to open valve 22.

In the event that a low rate of heating takes place at the same time that all of valves 17 are 25 open, overflow valve 30 will be closed and valve 32 will be open. Under these conditions the cold water discharged from the consumers through conduit 18 will pass into the lower part of accumulator 19 and will displace hot water from the 30 upper part of the accumulator which will flow through conduits 29, 31 and 21 into the generator. It will thus be seen that the generator is supplied with hot water at such times as the heat input thereof is low, regardless of the demand of the 35 consumers.

Inasmuch as hot water has a lower specific gravity than cold water and inasmuch as hot water is admitted to the top of the accumulator while cold water is admitted to the bottom, it follows that the water contained in the upper part of the accumulator will be hot while that contained in the lower part will be cold. On the drawings a line of demarcation between the hot and the cold water in the accumulator is represented 45 at 34. However, it will be understood that no sharp line of demarcation exists. Nevertheless, there is a very distinct difference in temperature between the water in the upper part of the accumulator and that in the lower part.

It will be understood that the valves 30, 32 and 22 need not be either completely closed or completely open, but that these valves may take intermediate positions such that conditions of equilibrium will be maintained in the system.

If the resistances to flow in conduits 21 and 29 are fixed orifices or manually operable valves which, when once adjusted remain fixed, the operation of the system is substantially the same as when overflow valves 22 and 30 are partially open. 60 If overflow valve 30 is replaced by a fixed orifice which offers a greater resistance to flow than do the consumers, then substantially all of the water from pump 14 will flow through the consumers if valves 17 are open. However if one or more of valves 17 are closed the resistance to flow through the consumers is increased and more water passes through the fixed orifice in conduit 29. Likewise, as long as valve 32 is open, the resistance to flow through conduit 31 is less than 65 through a fixed orifice in conduit 21 in place of overflow valve 22, and substantially all of the water will pass through valve 32 in preference to the orifice. However, if valve 32 is closed the only remaining path is through conduit 21 and 70 75

the orifice therein, and the water will necessarily follow this path.

In the modification shown in Fig. 2 the only variation from that shown in Fig. 1 is the means for controlling valve 32. In Fig. 2 this valve is controlled in response to the temperature of the water delivered from generator 10 through conduit 13. To accomplish this a thermostatic element 35 is located in conduit 13 and is connected 10 by means of a tube 36 to the upper part of the cylinder of valve 32.

The operation of this modification is substantially the same as that described in connection with Fig. 1, except that valve 32 is controlled by the temperature of the water discharged from the generator. If the temperature of this water is high the fluid in thermostatic element 35 expands and closes valve 32. In this event, cold water is forced from the lower part of the accumulator 20 through conduits 18 and 21 into the generator. On the other hand, if the temperature of the water flowing through conduit 21 to the generator becomes low, valve 32 opens and hot water from the upper part of the accumulator passes through 25 conduits 29, 31 and 21 to the generator.

Instead of having thermostatic element 35 located in conduit 13, it might be located directly in the generator as shown in Fig. 5. In this case the operation of the system would be the same 30 as that of the system shown in Fig. 1, inasmuch as there is a direct relationship between the temperature of the water in generator 10 and the pressure existing in the generator.

In Fig. 3 there is shown an embodiment of my invention which differs from that shown in Fig. 1 in that valve 32 is replaced with an overflow valve 40. Valve 40 is responsive to the pressure ahead of the valve in conduit 31 in the direction 40 of flow of fluid therethrough. An increase in pressure in this portion of conduit 31 causes the valve 40 to open. The embodiment shown in Fig. 3 also differs from that shown in Fig. 1 in that overflow valve 23 is replaced by a valve 41, which is responsive to the pressure or temperature existing in the generator 10. Valve 41 is arranged so that an increase in pressure or temperature in the generator causes the valve to open.

In the operation of the embodiment shown in Fig. 3, if the temperature or pressure in the generator falls below a predetermined value, valve 41 is closed and the pump 14 builds up pressure in the system, thereby causing overflow valve 40 to open. Hot water is thus supplied through 45 conduits 31 and 21 to the generator. This hot water is supplied to conduit 31 from the accumulator 19 if overflow valve 30 is closed, and from conduit 29 if the overflow valve is open due to the valves 17 being closed, or partially from 50 both if one or two of the valves 17 are closed and the remaining valves 17 open.

In Fig. 4 the valve 32 of Fig. 3 is replaced by a fixed orifice 43. The resistance to flow through orifice 43 is such that a greater percentage of fluid will flow through valve 41 if the latter valve is open. If valve 41 is closed all of the fluid supplied to the generator must pass through orifice 43.

While I have described several more or less specific embodiments of my invention, it is to be understood that modifications thereof fall within its scope, which is to be determined by the appended claims viewed in the light of the prior art.

Having thus described my invention what I claim is:

1. In a hot water accumulating system, a hot water generator, a heat consumer and an accumulator interconnected to form a closed system, means for withdrawing hot water from said generator, means responsive to the demand of said consumer for by-passing hot water around said consumer, means for conveying by-passed hot water to said accumulator, means for conveying 10 cold water discharged from said consumer to said accumulator, means for conveying hot water from said accumulator to said generator, means for conveying cold water from said accumulator to said generator, and means operative in accordance with pressure variations in said generator 15 for controlling admission of hot water and cold water, respectively, from said accumulator to said generator so as to maintain the pressure within said generator substantially constant. 20

2. In a hot water accumulating system, a hot water generator, a heat consumer and an accumulator interconnected to form a closed system, means for withdrawing hot water from said generator, means responsive to the demand of said consumer for by-passing hot water around said consumer, means for conveying by-passed hot water to said accumulator, means for conveying cold water discharged from said consumer to said accumulator, means for conveying hot water 30 from said accumulator to said generator, means for conveying cold water from said accumulator to said generator, and means operative in accordance with pressure variations in said generator 35 for admitting cold water from said accumulator to said generator upon a rise of pressure and for admitting hot water from said accumulator to said generator upon a fall in pressure.

3. In a hot water accumulating system, a hot water generator, a heat consumer, a water pump, 40 means for conveying water from said generator to said pump, a first conduit connecting the outlet of said pump with said consumer, a hot water accumulator, a second conduit connecting said first conduit with said accumulator, a resistance 45 to flow disposed in said second conduit, means for conveying water from said consumer to said accumulator, a third conduit connecting the lower part of said accumulator with said generator, a resistance to flow disposed in said third conduit, a 50 fourth conduit connecting the upper part of said accumulator to said generator, a resistance to flow in said fourth conduit, and means operative in accordance with temperature variations of the water in said generator for varying one of the 55 two last mentioned resistances in such manner that an increase in said temperature increases the relative resistance to flow through said fourth conduit as compared with said third conduit.

4. In a hot water accumulating system, a hot 60 water generator, a heat consumer, a water pump, means for conveying water from said generator to said pump, a first conduit connecting the outlet of said pump with said consumer, a hot water accumulator, a second conduit connecting said 65 first conduit with said accumulator, a resistance to flow disposed in said second conduit, means for conveying water from said consumer to said accumulator, a third conduit connecting the lower part of said accumulator with said generator, a 70 resistance to flow disposed in said third conduit, a fourth conduit connecting the upper part of said accumulator to said generator, a resistance to flow in said fourth conduit, and means operative in accordance with increase in temperature of 75

the water in said generator for increasing the resistance in said fourth conduit.

5. In a hot water accumulating system, a hot water generator, a heat consumer, a water pump, means for conveying water from said generator to said pump, a first conduit connecting the outlet of said pump with said consumer, a hot water accumulator, a second conduit connecting said first conduit with said accumulator, a resistance to flow disposed in said second conduit, means for conveying water from said consumer to said accumulator, a third conduit connecting the lower part of said accumulator with said generator, a resistance to flow disposed in said third conduit, a fourth conduit connecting the upper part of said accumulator to said generator, a resistance to flow in said fourth conduit, and means operative in accordance with pressure variations with said generator for varying one of the two last mentioned resistances in such manner that an increase in said pressure increases the relative resistance to flow through said fourth conduit as compared with said third conduit.

6. In a hot water accumulating system, a hot water generator, a heat consumer, a water pump, means for conveying water from said generator to said pump, a first conduit connecting the outlet of said pump with said consumer, a hot water accumulator, a second conduit connecting said first conduit with said accumulator, a resistance to flow disposed in said second conduit, means for conveying water from said consumer to said accumulator, a third conduit connecting the lower part of said accumulator with said generator, a resistance to flow disposed in said third conduit, a fourth conduit connecting the upper part of said accumulator to said generator, a resistance to flow in said fourth conduit, and means operative in accordance with increase in pressure within said generator for increasing the resistance in said fourth conduit.

7. In a hot water accumulating system, a hot water generator, a heat consumer, a water pump, means for conveying water from said generator to said pump, a first conduit connecting the outlet of said pump with said consumer, a hot water accumulator, a second conduit connecting said first conduit with said accumulator, a resistance to flow disposed in said second conduit, means for conveying water from said consumer to said accumulator, a third conduit connecting the lower part of said accumulator with said generator, a resistance to flow disposed in said third conduit, a fourth conduit connecting the upper part of said accumulator to said generator, a resistance to flow in said fourth conduit, and means operative in accordance with temperature variations of the water flowing through the first mentioned means for varying one of the two last mentioned resistances in such manner that an increase in said temperature increases the relative resistance to flow through said fourth conduit as compared with said third conduit.

8. In a hot water accumulating system, a hot water generator, a heat consumer, a water pump, means for conveying water from said generator to said pump, a first conduit connecting the outlet of said pump with said consumer, a hot water accumulator, a second conduit connecting said first conduit with said accumulator, a resistance to flow disposed in said second conduit, means for conveying water from said consumer to said accumulator, a third conduit connecting the lower part of said accumulator with said generator, a resistance to flow disposed in said third conduit,

a fourth conduit connecting the upper part of said accumulator to said generator, a resistance to flow in said fourth conduit, and means operative in accordance with increase in temperature of the water flowing through the first mentioned means for increasing the resistance in said fourth conduit.

9. In a hot water accumulating system, a hot water generator, a heat consumer, a water pump, means for conveying water from said generator to said pump, a first conduit connecting the outlet of said pump with said consumer, a hot water accumulator, a second conduit connecting said first conduit with said accumulator, an overflow valve disposed in said second conduit, means for conveying water from said consumer to said accumulator, a third conduit connecting the lower part of said accumulator with said generator, an overflow valve disposed in said third conduit, a fourth conduit connecting the upper part of said accumulator to said generator, a valve in said fourth conduit, and means for closing said valve in accordance with increase in temperature of the water in said generator.

10. In a hot water accumulating system, a hot water generator, a heat consumer, a water pump, means for conveying water from said generator to said pump, a first conduit connecting the outlet of said pump with said consumer, a hot water accumulator, a second conduit connecting said first conduit with said accumulator, an overflow valve disposed in said second conduit, means for conveying water from said consumer to said accumulator, a third conduit connecting the lower part of said accumulator with said generator, an overflow valve disposed in said third conduit, a fourth conduit connecting the upper part of said accumulator to said generator, a valve in said fourth conduit, and means for closing said valve in accordance with increase in pressure occurring within said generator.

11. In a hot water accumulating system, a hot water generator, a heat consumer, a water pump, means for conveying water from said generator to said pump, a first conduit connecting the outlet of said pump with said consumer, a hot water accumulator, a second conduit connecting said first conduit with said accumulator, an overflow valve disposed in said second conduit, means for conveying water from said consumer to said accumulator, a third conduit connecting the lower part of said accumulator with said generator, an overflow valve disposed in said third conduit, a fourth conduit connecting the upper part of said accumulator to said generator, a valve in said fourth conduit, and means for closing said valve in accordance with increase in temperature of water flowing through said first mentioned means.

12. In a hot water accumulating system, a hot water generator, a heat consumer, an accumulator, means for conveying hot water from said generator to said consumer, means for conveying hot water from said generator to said accumulator, means for conveying cooled water from said consumer to said accumulator, means for conveying hot water from said accumulator to said generator, means for conveying cold water from said accumulator to said generator, and automatic means for controlling the admission of hot and cold water to said generator operative to maintain a substantially constant temperature in said generator.

13. In a hot water accumulating system, a hot water generator, a heat consumer, an accumulator, means for conveying hot water from said

- generator to said consumer, means for conveying hot water from said generator to said accumulator, means for conveying cooled water from said consumer to said accumulator, means for conveying hot water from said accumulator to said generator, means for conveying cold water from said accumulator to said generator, and automatic means for controlling the admission of hot and cold water to said generator operative to maintain the temperature of the hot water withdrawn from said generator at a substantially constant temperature.

14. In a hot water accumulating system, a hot water generator, a heat consumer, a water pump, means for conveying water from said generator to said pump, a first conduit connecting the outlet of said pump with said consumer, a hot water accumulator, a second conduit connecting said first conduit with said accumulator, a resistance to flow disposed in said second conduit, means for conveying water from said consumer to said accumulator, a third conduit connecting the lower part of said accumulator with said generator, a resistance to flow disposed in said third conduit, a fourth conduit connecting the upper part of said accumulator to said generator, a resistance to flow in said fourth conduit, and means operative in accordance with increase in temperature of the water in said generator for decreasing the resistance in said third conduit.

15. In a hot water accumulating system, a hot water generator, a heat consumer, a first conduit for conducting water from said generator to said consumer, a hot water accumulator, a second conduit connecting said first conduit with said accumulator, a resistance to flow disposed in said second conduit, means for conveying water from said consumer to said accumulator, a third conduit connecting the lower part of said accumulator with said generator, a resistance to flow disposed in said third conduit, a fourth conduit connecting the upper part of said accumulator to said generator, a resistance to flow in said fourth conduit, and means operative in accordance with increase in temperature of the water in said generator for decreasing the resistance in said third conduit.

16. In a hot water accumulating system, a hot water generator, a heat consumer, a first conduit for conducting water from said generator to said consumer, a hot water accumulator, a second conduit connecting said first conduit with said accumulator, a resistance to flow disposed in said second conduit, means for conveying water from said consumer to said accumulator, a third conduit connecting the lower part of said accumulator with said generator, a resistance to flow disposed in said third conduit, a fourth conduit connecting the upper part of said accumulator to said generator, a resistance to flow in said fourth conduit, means for producing flow of water from said generator through said first conduit, and means operative in accordance with temperature variations of water in said generator for varying one of the two last mentioned resistances in such manner that an increase in said temperature increases the relative resistance to flow through said fourth conduit as compared with said third conduit.

17. In a hot water accumulating system, a hot water generator, a heat consumer, a first conduit for conducting water from said generator to said consumer, a hot water accumulator, a second conduit connecting said first conduit with said accumulator, a resistance to flow disposed in said second conduit, means for conveying water from said consumer to said accumulator, a third conduit connecting the lower part of said accumulator with said generator, a resistance to flow disposed in said third conduit, a fourth conduit connecting the upper part of said accumulator to said generator, a resistance to flow in said fourth conduit, means for producing flow of water from said generator through said first conduit, and means operative in accordance with increase in temperature of water in said generator for increasing the resistance in said fourth conduit.

18. In a hot water accumulating system, a hot water generator, a heat consumer, a first conduit for conducting water from said generator to said consumer, a hot water accumulator, a second conduit connecting said first conduit with said accumulator, an overflow valve disposed in said second conduit, means for conveying water from said consumer to said accumulator, a third conduit connecting the lower part of said accumulator with said generator, an overflow valve disposed in said third conduit, a fourth conduit connecting the upper part of said accumulator to said generator, a valve in said fourth conduit, means for producing flow of water from said generator through said first conduit, and means for closing said valve in accordance with increase in temperature of the water in said generator.

19. In a hot water accumulating system, a hot water generator, a heat consumer, a first conduit for conducting water from said generator to said consumer, a hot water accumulator, a second conduit connecting said first conduit with said accumulator, a resistance to flow disposed in said second conduit, means for conveying water from said consumer to said accumulator, a third conduit connecting the lower part of said accumulator with said generator, a resistance to flow disposed in said third conduit, a fourth conduit connecting the upper part of said accumulator to said generator, a resistance to flow in said fourth conduit, means for producing flow of water from said generator through said first conduit, and means operative in accordance with temperature variations of the water flowing through said first conduit for varying one of the two last mentioned resistances in such manner that an increase in said temperature increases the relative resistance to flow through said fourth conduit as compared with said third conduit.

20. In a hot water accumulating system, a hot water generator, a heat consumer, a first conduit for conducting water from said generator to said consumer, a hot water accumulator, a second conduit connecting said first conduit with said accumulator, a resistance to flow disposed in said second conduit, means for conveying water from said consumer to said accumulator, a third conduit connecting the lower part of said accumulator with said generator, a resistance to flow disposed in said third conduit, a fourth conduit connecting the upper part of said accumulator to said generator, a resistance to flow in said fourth conduit, means for producing flow of water from said generator through said first conduit, and means operative in accordance with increase in temperature of the water flowing through said first conduit for increasing the resistance in said fourth conduit.

21. In a hot water accumulating system, a hot water generator, a heat consumer, a first conduit for conducting water from said generator to said consumer, a hot water accumulator, a second con-

duit connecting said first conduit with said ac-
cumulator, an overflow valve disposed in said
second conduit, means for conveying water from
said consumer to said accumulator, a third con-
duit connecting the lower part of said accumu-
lator with said generator, an overflow valve dis-
posed in said third conduit, a fourth conduit
connecting the upper part of said accumulator to

said generator, a valve in said fourth conduit,
means for producing flow of water from said
generator through said first conduit, and means
for closing said valve in accordance with increase
in temperature of water flowing through said
first conduit. 5

CARL FÖHL.
